UNITED STATES PATENT OFFICE.

ROY ARCHER OSTRAM, OF DULUTH, MINNESOTA, ASSIGNOR TO DULUTH SHOW CASE COMPANY, OF DULUTH, MINNESOTA, A CORPORATION OF MINNESOTA.

STORE-FIXTURE.

1,272,989.

Specification of Letters Patent. Patented July 16, 1918.

Application filed November 22, 1916. Serial No. 132,782.

To all whom it may concern:

Be it known that I, ROY ARCHER OSTRAM, a citizen of the United States, residing at Duluth, in the county of St. Louis and State 5 of Minnesota, have invented certain new and useful Improvements in Store-Fixtures, of which the following is a specification.

This invention relates in general to store fixtures and more particularly to a display 10 and storage case for articles of merchandise.

In handling lines of merchandise, such for example as hardware where the stock comprises a multitude of relatively small 15 articles, much difficulty is experienced by the storekeeper in maintaining the stock in readily accessible and salable condition. Stock cases have heretofore been devised in which different species of articles are displayed in separate drawers with a sample 20 of each species secured to the face of the drawer in which it is contained. A number of different species of each genus or class of articles are frequently carried in stock 25 and this necessitates the removal by the salesman of the several species from the drawers or of all of the drawers containing the genus or class of articles desired whenever a sale is contemplated, so that the prospective 30 buyer may be acquainted with the selection of merchandise offered by the storekeeper and select therefrom. The customer thereby obtains access to the stock, frequent handling of which results in deterioration 35 of the finish and ultimately renders a portion of the stock unsalable. Moreover, in making sales according to this system much time is lost owing to the difficulty of finding desired articles and 40 turning them to their proper receptacles when no longer needed and sales are lost because of lack of knowledge of the stock by salesmen.

It is the object of my invention to provide 45 a display door for store fixture cabinets adapted for the permanent exhibition of samples of the goods contained in the cabinet behind the door and to mount said samples on one or more removable back 50 panels of the door which can be readily taken out for inspection of the samples in making sales and replaced without disturbing the samples or any other panels and

without handling the stock from which the goods sold by the samples are taken. 55

Further objects and advantages of my invention will be apparent as it is better understood by reference to the following specification when read in connection with the accompanying drawing, illustrating the 60 preferred embodiment thereof, in which—

Figure 1 is a view in perspective of a display and storage case according to my invention, and

Fig. 2 is an enlarged detail in section of 65 the display portion of the case.

In the drawings I have illustrated the invention embodied in a cabinet having a plurality of drawers 2 which are normally concealed and protected by hinged doors 3. 70 The cabinet may be built in any size and shape desired, in one unit or in sections and provided with shelves instead of the drawers 2, as may be desired. The cabinet 1 may rest on a support as indicated in the 75 drawing which may contain storage compartments or the cabinet may itself be provided with supporting means and in fact may be supported in any suitable manner.

In the particular form of the invention 80 shown in the drawings the door comprises a facing 4, a glass front 5 mounted in the facing, side walls 6, and bottom and top walls 7 mounted on the facing at the back thereof. The back of the door may be made of 85 one or more removable panels, but I have shown four panels 9 disposed between the channel members 8 which are so arranged that the distance between the bottoms of 90 oppositely disposed channels is somewhat greater than the width of the panel to be inserted therein so that by grasping the handles 10 the panels may be readily removed and disposed upon the counter (not 95 shown). Thus the articles of merchandise which are secured to the panels may be displayed to the prospective customer.

It is my intention that each of the articles secured to one of the panels 9 be provided with a suitable key number, which number 100 is duplicated upon one of the drawers 2 in which articles corresponding to the sample on a panel 9 are disposed. Consequently when the customer has selected the desired article from those available, as shown by 105 the samples on the panel 9, the salesman

turns to the drawer bearing the corresponding number and obtains the article desired. The panel 9 bearing the samples may then be quickly returned to its normal position where the samples are constantly displayed.

From the foregoing it will be apparent that I have perfected a display and storage case providing for the maximum efficiency of the salesman by making it possible for him to work more rapidly. The maximum efficiency of the case itself is also insured because it provides for the continuous display of the stock, thus increasing the sales while maintaining the stock in an orderly condition and preserving it from deterioration.

It will be apparent that various changes may be made in the form, construction and arrangement of the parts without departing from the spirit and scope of the invention or sacrificing any of its material advantages, the form hereinbefore described being merely a preferred embodiment thereof.

I claim:

1. In a store fixture, the combination of a cabinet embodying a plurality of compartments for the reception of merchandise and a closure hinged to said cabinet to swing about a substantially vertical axis and normally concealing said compartments, said closure comprising a frame, a transparent front rigidly mounted in said frame, and a sectional back mounted in and movable with said frame and adapted to support individual articles of merchandise, the separate sections of said back being individually removable from said frame to simultaneously and collectively remove the articles of merchandise secured thereto.

2. In a store fixture the combination of a cabinet embodying a plurality of compartments for the reception of merchandise and a closure hinged to said cabinet to swing about a substantially vertical axis and normally concealing said compartments, said closure comprising a frame, a transparent front rigidly mounted in said frame and a back comprising a plurality of sections arranged one above the other and adapted to support individual articles of merchandise, said back being mounted in and movable with said frame and said sections being individually removable from said frame to simultaneously and collectively remove the articles of merchandise secured thereto.

3. In a store fixture, a display case comprising a frame hingedly mounted for swinging movement about a substantially vertical axis, a transparent front rigidly mounted in said frame and a back mounted in and movable with said frame and consisting of a plurality of transverse members having channels therein, and a plurality of panels mounted between said members and adapted to support individual articles of merchandise, said panels being narrower than the distance between the bottoms of opposite channels whereby the panels are readily inserted and removed.

ROY ARCHER OSTRAM.
